Primary Examiner — Brett Miller*Assistant Examiner* — Nader Abadir(74) *Attorney, Agent, or Firm* — Browdy and Neimark, PLLC(57) **CLAIM**

The ornamental design for a cup as shown and described.

DESCRIPTION

FIG. 1 is a perspective view of a cup showing my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The even spaced broken lines shown in the drawings depict portions of the article that form no part of the claimed design.

The blank regions from no part of the claimed design.

1 Claim, 8 Drawing Sheets(56)
